(57) **ABSTRACT**

The present invention provides a circuit, which includes a first sound signal input end, a second sound signal input end, a power amplifier, a capacitor, a low frequency sounding module and a high frequency sounding module. The present invention also provides a sounding device applying the circuit provided by the present invention. Compared with the related art, the present invention provides a sounding device with simplified structure and wide application.

TECHNICAL FIELD

The disclosure relates to the field of electro-acoustic transducers, in particular to a circuit for a sounding device used in a portable mobile electronic product.

BACKGROUND ART

The sounding device is widely used in portable mobile electronic products, such as mobile phones, the audio signal is converted into sound for playback, the sounding device has large loudness, and the effect of low-frequency sound and high-frequency sound is good. The circuit used to drive the sounding device has also become an important part of portable mobile electronic products.

The sounding device circuit of the related art includes a plurality of the sounding devices, a power amplifier, and a capacitor.

However, the sounding device circuit of the related art requires multiple the sounding devices in the terminal device application, for example, a plurality of the sounding devices are required on a mobile phone to generate low-frequency sounds, generate high-frequency sounds, and use them as the receiver. Please refer to FIG. 1, FIG. 1 is a structural block view of one of the application scenarios of the sounding device of the related technology on the terminal device: A power amplifier P1 is used to achieve low-frequency sound and high-frequency sound. In specific application, the music signal equipment S1 divides the music signal into two signals after passing through the power amplifier P1. One channel is directly sent to the low pitch speaker U1, and the other channel is sent to the high pitch speaker U2 after connecting the capacitor C in series. In addition, the voice signal equipment S2 send the voice signal to the receiver U3. In this application scenario, the high pitch speaker U2 and the receiver U3 are two independent speakers, and the corresponding drivers are also separated. Please refer to FIG. 2, FIG. 2 is a structural block view of another application scenario of the sounding device of the related technology on the terminal device: The music signal equipment S1 sends its music signal to the low pitch speaker U1 after passing through the power amplifier P1, the music signal equipment S2 sends its music signal to the low pitch speaker U2 by connecting the power amplifier P2 and the capacitor C in series, the voice signal equipment S2 send the voice signal to the receiver U3. In this application scenario, the low pitch speaker U, the high pitch speaker U2 and the receiver U3 are three independent speakers, and the corresponding drivers are also separated, and at least two the power amplifiers are required. The above-mentioned technical solution adopts many devices, and the driving circuit is complicated, which is not conducive to the integrated application.

Therefore, it is necessary to provide a new circuit and a new sounding device to solve the above technical problems.

SUMMARY OF THE INVENTION

The main purpose of the present invention is to provide a circuit and a sounding device with a small number of the power amplifiers, simplified structure and wide applications.

In order to achieve the above-mentioned object, the present disclosure provides a circuit, applied to a sounding device, including: a first sound signal input end for receiving sound signals with high-pitch and low-pitch; a second sound signal input end for receiving voice signals; a power amplifier having a positive end connected to the first sound signal input end, and a negative end connecting to ground; a low frequency sounding module connecting to the output end of the power amplifier; a high frequency sounding module having a first input end, and a second input end; and a capacitor having a first end connecting to an output end of the power amplifier, and a second end connecting to the first input end of the high frequency sounding module. The second sound signal input end is connected to the second input end of the high frequency sounding module.

The present disclosure further provides a sounding device, incorporating the circuit as described above, including a first vibration system for vibrating and generating low-pitch sound, and a second vibration system for vibrating and generating high-pitch sound and for serving as a receiver function to sound; wherein the output end of the power amplifier is connected to the first vibration system; the second end of the capacitor and the second sound signal input end are both connected to the second vibration system.

In addition, the sounding device further comprises a frame and a magnetic circuit system fixed on the frame; wherein the first vibration system and the second vibration system are coaxially arranged and located on opposite sides of the magnetic circuit system, respectively; the first vibration system includes a first diaphragm fixed on the frame and a first voice coil fixed on the first diaphragm; the second vibration system includes a second diaphragm fixedly supported on the magnetic circuit system and a second voice coil that drives the second diaphragm to vibrate and produce sound; the magnetic circuit system includes a first magnetic gap and a second magnetic gap, the first magnetic gap is arranged around the second magnetic gap; the first voice coil is inserted in the first magnetic gap and drives the first diaphragm to vibrate to generate low-pitch sound, the second voice coil is inserted in the second magnetic gap and drives the second diaphragm to vibrate to generate high-pitch sound.

In addition, the magnetic circuit system includes a magnetic yoke, a primary magnet group respectively fixed on the side of the magnetic yoke close to the first diaphragm, and an auxiliary magnet group surrounding the primary magnet group; the auxiliary magnet group is separated from the primary magnet group to form the first magnetic gap, and the magnetic yoke is annular; the primary magnet group includes an annular primary magnet, and a main pole plate covered and fixed on the primary magnet away from the magnetic yoke and an auxiliary magnet; the primary magnet and the inner wall of the magnetic yoke together form an inner cavity.

The main pole plate includes a main pole plate body fixed to the primary magnet, and a protruding part of the main pole plate extending from the inner periphery of the main pole plate body into the inner cavity; the auxiliary magnet cover is fixed on the side of the main pole plate body away from the magnetic yoke; the primary magnet and the magnetic yoke which jointly surround the protruding part of the main pole plate, and together with the protruding part of the main pole plate form the second magnetic gap with an opening facing the second vibration system; the protruding part of the main pole plate is a hollow ring.

In addition, the sounding device further comprises an annular support rack fixed on a side of the magnetic yoke

away from the frame, wherein a peripheral support of the second diaphragm is fixed on the side of the support rack away from the magnetic yoke; the magnetic circuit system and the second vibration system together form a lower cavity, and the lower cavity is connected with the second magnetic gap.

In addition, the second diaphragm includes a vibration part of the second diaphragm spaced from the magnetic yoke, a suspension of the second diaphragm extending from the outer periphery of the vibration part of the second diaphragm, and a connection part of the second diaphragm which is bent and extended from the suspension of the second diaphragm to the support rack; the connection part of the second diaphragm is fixed to the support rack; the second vibration system also includes a second skeleton; the side of the second skeleton close to the magnetic circuit system is fixed to the second voice coil, the side of the second skeleton away from the magnetic circuit system is fixed to the vibration part of the second diaphragm.

In addition, the second skeleton includes an annular a first fixed part, and an elastic arm that is bent and extended from the inner side of the first fixed part, and a second fixed part extending from the elastic arm away from the first fixed part; the connection part of the second diaphragm and the support rack are respectively fixed on opposite sides of the first fixed part, the vibration part of the second diaphragm and the second voice coil are respectively fixed on opposite sides of the second fixed part; the auxiliary magnet group includes the auxiliary magnet fixed on the magnetic yoke, and the auxiliary pole plate covered and fixed on the side of the auxiliary magnet away from the magnetic yoke; the second skeleton also includes a third fixed part that is bent and extended from the outside of the first fixed part to the direction of the frame; the auxiliary pole plate is fixed to the frame, the third fixed part is fixed to the side of the auxiliary pole plate away from the frame; the frame is rectangular; the number of the auxiliary pole plate is two, the two auxiliary pole plates are respectively located on opposite sides of the long axis of the frame.

In addition, the first diaphragm is annular, the inner peripheral side of the first diaphragm is fixed to the auxiliary magnet, and the outer peripheral side of the first diaphragm is fixed to the frame.

In addition, the first vibration system further includes a first skeleton which is annular, the first voice coil is fixed on one side of the first skeleton close to the magnetic circuit system; the first diaphragm includes a first folded ring which is annular and a second folded ring which is annular; the first folded ring is arranged around the second folded ring and is spaced apart from the first folded ring; the second folded ring is arranged to surround the auxiliary magnet, the inner peripheral side of the second folded ring is fixed to the outer side of the auxiliary magnet; the first skeleton acts as the dome of the first diaphragm, the outer peripheral side is fixed to the inner peripheral side of the first folded ring, the inner peripheral side is fixed to the outer peripheral side of the second folded ring; and the outer peripheral side of the first folded ring is fixed on the frame.

In addition, the first skeleton includes a first section which is annular, and a second section bent and extended from the inner peripheral side of the first section to the first voice coil, and a third section that is bent and extended from the inner peripheral side of the first section to the direction of the magnetic yoke; the first voice coil is fixed on the side of the second section close to the magnetic yoke, the side of the second section away from the magnetic yoke is fixed to the outer peripheral side of the second folded ring; the first

vibration system further includes an elastic support assembly arranged spaced from the first folded ring; one end of the elastic support assembly is fixed on the frame, and the other end of the elastic support assembly is fixed on the third section.

Compared with the related art, the circuit of the present invention is applied to the sounding device, the first sound signal input end with high-pitch sound and low-pitch sound is connected to the positive input end of the power amplifier, and then split into two route signals of high-pitch sound and low-pitch sound through the power amplifier. The splitted bass signal is directly input to the low frequency sounding module for sound, the splitted high-frequency signal is input to the high frequency sounding module by connecting the capacitor in series to produce sound. This structure allows the low frequency sounding module to generate low-pitch sound and the high frequency sounding module to generate high-pitch sound in the circuit of the present invention, the voice signal is input to the second input end of the high frequency sounding module through the second sound signal input end. When the high frequency sounding module of the present invention is used as the receiver, the low frequency sounding module can be used as the anti-phase muffler. At the same time, the circuit of the present invention only needs a power amplifier to realize various application functions, so that the structure is simple and the application is wide.

BRIEF DESCRIPTION OF DRAWING

FIG. 1 is a structural block view of one application scenario of a circuit of a related art on a terminal device.

FIG. 2 is a structural block view of another application scenario of a circuit of a related art on a terminal device.

FIG. 3 is a schematic view of the circuit of the present invention.

FIG. 4 is an isometric view of a sounding device of an embodiment of the present invention.

FIG. 5 is an exploded view of the sounding device of the present invention.

FIG. 6 is an exploded of the sounding device of the present invention from another aspect.

FIG. 7 is a cross-sectional view taken along line A-A in FIG. 4.

FIG. 8 is an enlarged view of Part B in FIG. 7.

FIG. 9 is an isometric view of an assembly of a primary magnet, an auxiliary magnet group and a first voice coil of the sounding device of the present invention.

FIG. 10 is an isometric view of an assembly of a magnetic yoke, a protruding part of a main pole plate and a second voice coil of the sounding device of the present invention.

FIG. 11 is a three-dimensional schematic view of the primary magnet group of the sounding device of the present invention.

DETAILED DESCRIPTION OF EXEMPLARY EMBODIMENT

The present disclosure will hereinafter be described in detail with reference to exemplary embodiments. To make the technical problems to be solved, technical solutions and beneficial effects of the present disclosure more apparent, the present disclosure is described in further detail together with the figures and the embodiments. It should be understood the specific embodiments described hereby are only to explain the disclosure, not intended to limit the disclosure.

Referring to FIG. 3, the present invention provides a circuit **200** and a sounding device **100**. The circuit **200** is applied to the sounding device **100**.

The circuit **200** includes a first sound signal input end IN1, a second sound signal input end S2, a power amplifier **201**, a capacitor **202** and a low frequency sounding module **101** and a high frequency sounding module **102**.

The first sound signal input end IN1 is used to receive a sound signal with high and low pitch, such as music signals. The second sound signal input end IN2 is used for receiving voice signals. The low frequency sounding module **101** is used to generate low frequency sound. The high frequency sounding module **102** is used to emit high frequency sound and can be used as the receiver function to generate sound.

The first sound signal input end IN1 is connected to the positive input end of the power amplifier **201**. The negative input end of the power amplifier **201** is connected to ground. The output end of the power amplifier **201** is respectively connected to the input end of the low frequency sounding module **101** and the first end of the capacitor. The second end of the capacitor is connected to the first input end of the high frequency sounding module **102**. The second sound signal input end IN2 is connected to the second input end of the high frequency sounding module **102**.

The first sound signal input end IN1 will have a music signal with high and low-pitch pass through the power amplifier **201**, then the signal is divided into two channels, and one channel is directly sent to the input end of the low frequency sounding module **101** for the low frequency sounding module **101** to generate low-frequency sound. The other path is sent to the first input end of the high frequency sounding module **102** through the capacitor **202** in series, for the high frequency sounding module **102** to generate high frequency sound. In addition, the second sound signal input end IN2 directly sends the voice signal to the second input end of the high frequency sounding module **102**. When the high frequency sounding module **102** is applied as the receiver, the low frequency sounding module **101** can be used as the anti-phase muffler. Therefore, the circuit **200** of the present invention only needs a power amplifier to realize various application functions, so that the structure is simple and the application is wide.

The present invention also provides a sounding device **100** in which the circuit **200** is applied. Specifically, the sounding device **100** includes a frame **10**, a first vibration system **20** respectively fixed on the frame **10** for vibrating to generate low-pitch sound, and a second vibration system **30** and a magnetic circuit system **40** for vibrating to generate high-pitched sound.

Wherein, the first vibration system **20** and the second vibration system **30** are coaxially arranged and located on opposite sides of the magnetic circuit system **40** respectively. This structure enables the second vibration system **30** to be arranged on the opposite side of the first vibration system **20** to emit sound, and enables the first vibration system **20** and the second vibration system **30** to achieve coaxial full-band sound, so that the circuit **200** of the present invention has a good acoustic effect.

At the same time, the second vibration system **30** can also be used as the receiver function to sound. Specifically, the second vibration system **30** and the magnetic circuit system **40** cooperate as the receiver, so that the first vibration system **10** and the magnetic circuit system **40** form a speaker which can be used as an anti-phase muffler.

In this embodiment, the first vibration system **20** and the magnetic circuit system **40** form the low frequency sounding

module **101**. The second vibration system **30** and the magnetic circuit system **40** form the high frequency sounding module **102**.

The first sound signal input end IN1 is connected to the positive input end of the power amplifier **201**. The negative input end of the power amplifier **201** is connected to ground. The output end of the power amplifier **201** is connected to the first input end of the sounding device **100** and the first end of the capacitor **202** respectively. The second end of the capacitor **202** is connected to the second input end of the sounding device **100**. The second sound signal input end S2 is connected to the third input ends of the sounding device **100**.

Wherein, the first input end of the sounding device **100** is connected to the first vibration system **20**. Both the second input end of the sounding device **100** and the third input end of the sounding device **100** are connected to the second vibration system **30**.

The first sound signal input end IN1 divides the music signal with treble and bass into two signals after passing through the power amplifier **201**. One route is directly sent to the low-pitch speaker formed by the magnetic circuit system **40** and the second vibration system **30**, the other route, through the capacitor **202** in series is sent to the magnetic circuit system **40** in the sounding device **100** and the high-pitch speaker formed by the second vibration system **30**. In addition, the second sound signal input end IN2 directly sends the voice signal to the magnetic circuit system **40** in the sounding device **100** and the high pitch speaker formed by the second vibration system **30**. When applying the second vibration system **30** and the magnetic circuit system **40** of the sounding device to form the speaker as the receiver, the first vibration system **20** and the magnetic circuit system **40** form the speaker which can act as the anti-phase muffler. Therefore, the circuit **200** of the present invention only needs a power amplifier to realize various application functions, so that the structure is simple and the application is wide.

In this embodiment, please refer to FIGS. 4-11 at the same time, the sounding device **100** includes a frame **10**, a first vibration system **20**, a second vibration system **30**, a magnetic circuit system **40** and a front cover **50** which are respectively fixed on the frame **10**. The frame **1** is annular.

The first vibration system **20** comprises a first diaphragm **1** that is fixed on the frame **10**, a first voice coil **201** fixed to the first diaphragm **1**, a first skeleton **2** which is annular and an elastic support assembly **202**. The first voice coil **201** is fixed to the side of the first skeleton **2** close to the magnetic circuit system **40**.

The second vibration system **30** is disposed on the side of the magnetic circuit system **40** away from the first vibration system **20** with space. The second vibration system **30** includes a second diaphragm **3**, which is fixedly supported on the magnetic circuit system **40**, a second voice coil **301** that drive the second diaphragm **3** to vibrate and produce sound and a second skeleton **4**.

The magnetic circuit system **40** includes a magnetic yoke **5**, a primary magnet group **6** respectively fixed on the magnetic yoke **5** near the first diaphragm **1** side, an auxiliary magnet group **7** surrounding the primary magnet group **6**.

The magnetic yoke **5** is annular. The second diaphragm **3** is spaced apart from the magnetic yoke **5**.

The primary magnet group **6** includes a primary magnet **61** which is annular, a main pole plate **62** covered and fixed on the side of the primary magnet **61** away from the

magnetic yoke **5**. The inner wall of the primary magnet **61** and the inner wall of the magnetic yoke **5** together form an inner cavity **402**.

The magnetic circuit system **40** includes a first magnetic gap **401** and a second magnetic gap **403**. The first magnetic gap **401** is arranged around the second magnetic gap **403**. In this embodiment, a second magnetic gap **403** is provided on the side of the magnetic circuit system **40** away from the first vibration system **20**. Specifically, the main pole plate **62** includes a main pole plate body **621** fixed on the primary magnet **61**, and a protruding part of the main pole plate **622** extending from the inner periphery of the main pole plate body **621** to the inner cavity **402** by bending. The primary magnet **61** and the magnetic yoke **5** jointly surrounding the protruding part of the main pole plate **622**, and together with the protruding part of the main pole plate **622** form the second magnetic gap **403** with an opening facing the second vibration system **30**. The second voice coil **301** is inserted in the second magnetic gap **403** and drives the second diaphragm **3** to vibrate and sound, so that the second vibration system **30** and the magnetic circuit system **40** form a high-pitch speaker, it is realized that the sounding device **100** provides a high-pitched sound effect function and can be used as the receiver, so that the circuit **200** has a simple structure and is widely used.

The auxiliary magnet group **7** is spaced from the primary magnet group **6** to form the first magnetic gap **401**. The first voice coil **201** is inserted into the first magnetic gap **401** and drives the first diaphragm **1** to vibrate and produce sound. This structure enables the first voice coil **201** of the first vibration system **20** to be inserted into the first magnetic gap **401** and drive the first diaphragm **1** to vibrate to emit low-frequency sound, so that the first vibration system **20** and the magnetic circuit system **40** form a low-pitch speaker. It is realized that the sounding device **100** provides a bass sound effect function, so that the circuit **200** has good acoustic performance and is widely used.

The second diaphragm **3** and the first diaphragm **1** are respectively disposed on opposite sides of the sounding device **100**. The second voice coil **301** and the first voice coil **201** are coaxially arranged. This structure allows the second vibration system **30** of the formed high pitch speaker to be disposed on the opposite side of the first vibration system **20** of the formed low pitch speaker to generate sound. This structure enables the first vibration system **20** and the second vibration system **30** to achieve coaxial full-band sound, so that the sounding device **100** of the present invention has good acoustic performance. When the second vibration system **30** and the magnetic circuit system **40** of the sounding device **100** of the present invention are applied to form the high pitch speaker as the receiver, the low pitch speaker formed by the first vibration system **20** and the magnetic circuit system **40** can be used as the anti-phase muffler. Meanwhile, the circuit **200** of the present invention only needs a power amplifier to realize various application functions, so that the circuit **200** has a simple structure and is widely used.

In this embodiment, the main pole plate **62** is provided with a middle hole **620** penetrating the main pole plate **62**. The middle hole **620** penetrates the main pole plate body **621** and the protruding part of the main pole plate **622** in sequence. The middle hole **620** forming a main pole plate **62** with a hollow middle part is provided. The protruding part of the main pole plate **622** extends to the inner cavity **402** so that the middle hole **620** is connected with the inner cavity **402** to form a big empty cavity, the empty cavity improves the high frequency performance of the sounding device **100**.

This structure advantageously improves the good acoustic performance of the high pitch speaker formed by the second vibration system **30** and the magnetic circuit system **40**, and good acoustic performance when used as the receiver.

In this embodiment, the magnetic field of the primary magnet group **6** is strengthened. The primary magnet group **6** also includes an auxiliary magnet **63** fixed on the side of the main pole plate body **621** away from the magnetic yoke **5** is covered. The auxiliary magnet **63** closes the middle hole **620**, what is achieved is that the second vibration system **30** and the magnetic circuit system **40** form good acoustic performance of the high pitch speaker, and good acoustic performance when used as the receiver.

In this embodiment, the first diaphragm **1** is annular. The inner peripheral side of the first diaphragm **1** is fixed to the auxiliary magnet **63**. The outer peripheral side of the first diaphragm **1** is fixed to the frame **10**. Specifically, the first diaphragm **1** includes a first folded ring **11** that is annular and a second folded ring **12** that is annular. The first folded ring **11** is arranged around the second folded ring **12** and is spaced apart from the first folded ring **11**. The second folded ring **12** is arranged around the auxiliary magnet **63**. The inner peripheral side of the second folded ring **12** is fixed to the outer side of the auxiliary magnet **63**. The first skeleton **2** acts as the dome of the first diaphragm **1**, the outer peripheral side of the first skeleton **2** is fixed on the inner peripheral side of the first folded ring **11**, the inner peripheral side of the first skeleton **2** is fixed on the outer peripheral side of the second folded ring **12**.

The outer peripheral side of the first folded ring **11** is fixed on the frame **10**. This structure enables the thickness of the sounding device **100** of the present invention to reuse the height of the magnetic circuit system **40**. The first diaphragm **1** of the first vibration system **20** is arranged outside the auxiliary magnet **63**, the thickness of the sounding device **100** occupied by the low pitch speaker of the first vibration system **20** and the magnetic circuit system **40** is reduced, and the size of the low pitch speaker is increased at the same time, so that the acoustic performance of the sounding device **100** in terms of bass is improved, so that the circuit **200** has good acoustic performance and is widely used.

In this embodiment, the first skeleton **2** is fixed to the first voice coil **201** on the side close to the magnetic circuit system **40**. Specifically, the first skeleton **2** includes a first section **21** which is annular, a second section **22**, which is bent and extended to the first voice coil **201** from the inner peripheral side of the first section **21**, and a third section **23** which is bent and extended from the inner peripheral side of the first section **21** to the direction of the magnetic yoke **5**. The first voice coil **201** is fixed to the side of the second section **22** close to the magnetic yoke **5**. The side of the second section **22** away from the magnetic yoke **5** is fixed to the outer peripheral side of the second folded ring **12**. The structure of the first skeleton **2** is beneficial to make the thickness of the sounding device **100** very thin, and at the same time increase the size of the low pitch speaker, thereby improving the acoustic performance of the sounding device **100** in terms of bass, so that the acoustic performance of the circuit **200** is good and Wide range of applications.

In this embodiment, the first vibration system **20** further includes an elastic support assembly **202** arranged with space from the first folded ring **11**. One end of the elastic support assembly **202** is fixed to the frame **10**. The other end of the elastic support assembly **202** is fixed to the third section **23**. On the one hand, the elastic support assembly **202** is used to strengthen the vibration effect of the first diaphragm **1** and improve the acoustic performance of the

sounding device **100**. On the other hand, it is used to balance the swing of the first vibration system **20** and improve the stability of the sounding device **100**, so that the sounding device **100** has good acoustic performance and is widely used.

In this embodiment, the frame **10** is rectangular. The number of the elastic support assembly **202** is two. The two elastic support assemblies **202** are located on opposite sides of the short axis of the frame **10**, respectively. The two elastic support assemblies **202** symmetrically distributed support the first voice coil **201** more stably and better vibration reliability is achieved.

In this embodiment, the sounding device **100** further includes a support rack **60** which is annular. The support rack **60** is fixed on the side of the magnetic yoke **5** away from the frame **10**. The peripheral edge of the second diaphragm **3** is supported and fixed on the side of the support rack **60** away from the magnetic yoke **5**.

The magnetic circuit system **40** and the second vibration system **30** together form the lower cavity **404**. The lower cavity **404** is connected with the second magnetic gap **403**.

Specifically, the support rack **60** is provided with a leak hole **600** extending therethrough. The lower cavity **404** is connected with the outside through the leak hole **600**. The setting of the leak hole **600** is beneficial to balance the air pressure of the lower cavity **404** and the outside, so that the acoustic performance of the high pitch speaker formed by the magnetic circuit system **40** and the second vibration system **30** is improved, and it can be better converted into the receiver. Therefore, the sounding device **100** has good acoustic performance and is widely used.

In this embodiment, the second diaphragm **3** includes a vibration part of the second diaphragm **31**, spaced from the magnetic yoke **5**, a suspension of the second diaphragm **32** which is folded and extended from the outer periphery of the vibration part of the second diaphragm **31**, and a connection part of the second diaphragm **33** extending from the suspension of the second diaphragm **32** to the support rack **60**. The connection part of the second diaphragm **33** is fixed to the support rack **60**.

The side of the second skeleton **4** close to the magnetic circuit system **40** is fixed to the second voice coil **301**. The side of the second skeleton **4** away from the magnetic circuit system **40** is fixed to the vibration part of the second diaphragm **31**. Specifically, the second skeleton **4** includes a first fixed part **41** in the form of a ring, an elastic arm **42**, which is bent and extended from the inner side of the first fixed part **41**, and a second fixed part **43** extending away from the first fixed part **41** from the elastic arm **42**.

Wherein, the connection part of the second diaphragm **33** and the support rack **60** are respectively fixed on opposite sides of the first fixed part **41**. The vibration part of the second diaphragm **31** and the second voice coil **301** are respectively fixed on opposite sides of the second fixed part **43**. In the structure of the second skeleton **4**, the second diaphragm **3** is respectively fixed with the support rack **60** and the second voice coil **301**, the vibration effect of the vibration part of the second diaphragm **31** is enhanced and the reliability of the vibration part of the second diaphragm **31** is improved because of the elasticity of the elastic arm **42** of the second skeleton **4**, so that the stability and acoustic performance of the sounding device **100** are improved, so that the acoustic performance of the circuit **200** is good and widely used.

In this embodiment, the auxiliary magnet group **7** includes an auxiliary magnet **71** fixed to the magnetic yoke

5, an auxiliary pole plate **72** which is covered and fixed on the side of the auxiliary magnet **71** away from the magnetic yoke **5**.

The second skeleton **4** also includes a third fixed part **44** which is bent and extended from the outside of the first fixed part **41** to the direction of the frame **10**.

The auxiliary pole plate **72** is fixed to the frame **10**. The third fixed part **44** is fixed to the side of the auxiliary pole plate **72** away from the frame **10**. Wherein, the frame **10** is rectangular. The number of the auxiliary pole plates **72** is two. The two auxiliary pole plates **72** are located on opposite sides of the long axis of the frame **10**, respectively. This structure facilitates the fixing of the second diaphragm **3** on the frame **10**, thereby improving the stability and acoustic performance of the sounding device **100**.

The front cover **50** is covered and fixed on the second diaphragm **3** and together with the second diaphragm **3** forms a front sound cavity **51**. The front cover **50** is provided with a front sound hole **52** therethrough. The front sound cavity **51** is connected with the outside through the front sound hole **52**. The structure of the front sound cavity **51** is beneficial to improve the effect of the second diaphragm **3** to generate high-frequency sound. The front cover **50** protects the second diaphragm **3** from external damage, which is beneficial to be used as the receiver, thereby improving the stability and acoustic performance of the sounding device **100**, so that the circuit **200** has good acoustic performance and is widely used.

Compared with the related art, in the circuit of the present invention, it is applied to the sounding device, the first sound signal input end with high-pitch and low-pitch is connected to the positive input end of the power amplifier, at the same time, the power amplifier is divided into two path signals of high-pitch and low pitch, the separated high-pitch signal is directly input to the low frequency sounding module for sound, the separated low-pitch signal is input to the high frequency sounding module by connecting the capacitor in series to produce sound. This structure allows the low frequency sounding module to generate low-pitch sound and the high frequency sounding module to generate high-pitch sound. In the circuit of the present invention, the voice signal is input to the second input end of the high frequency sounding module through the second sound signal input end, when applying the high frequency sounding module of the present invention as the receiver, the low frequency sounding module can be used as the anti-phase muffler, at the same time, the circuit of the present invention only needs a power amplifier to realize various application functions, so that the structure is simple and the application is wide.

It is to be understood, however, that even though numerous characteristics and advantages of the present exemplary embodiments have been set forth in the foregoing description, together with details of the structures and functions of the embodiments, the disclosure is illustrative only, and changes may be made in detail, especially in matters of shape, size, and arrangement of parts within the principles of the invention to the full extent indicated by the broad general meaning of the terms where the appended claims are expressed.

What is claimed is:

1. A sounding device, incorporating a circuit, including a first vibration system for vibrating and generating low-pitch sound, and a second vibration system for vibrating and generating high-pitch sound and for serving as a receiver function to sound; wherein the circuit including: a first

11

sound signal input end for receiving sound signals with high-pitch and low-pitch; a second sound signal input end for receiving voice signals;

a power amplifier having a positive end connected to the first sound signal input end, and a negative end connecting to ground; a low frequency sounding module connecting to the output end of the power amplifier; a high frequency sounding module having a first input end, and a second input end; a capacitor having a first end connecting to an output end of the power amplifier, and a second end connecting to the first input end of the high frequency sounding module; wherein the second sound signal input end is connected to the second input end of the high frequency sounding module; the output end of the power amplifier is connected to the first vibration system; the second end of the capacitor and the second sound signal input end are both connected to the second vibration system;

the sounding device further comprising a frame and a magnetic circuit system fixed on the frame; wherein the first vibration system and the second vibration system are coaxially arranged and located on opposite sides of the magnetic circuit system, respectively; the first vibration system includes a first diaphragm fixed on the frame and a first voice coil fixed on the first diaphragm; the magnetic circuit system includes a magnetic yoke, a primary magnet group respectively fixed on the side of the magnetic yoke close to the first diaphragm, and an auxiliary magnet group surrounding the primary magnet group; the primary magnet group includes an annular primary magnet, and a main pole plate covered and fixed on the primary magnet away from the magnetic yoke and an auxiliary magnet; the first diaphragm is annular, the inner peripheral side of the first diaphragm is fixed to the auxiliary magnet, and the outer peripheral side of the first diaphragm is fixed to the frame.

2. The sounding device as described in claim 1, wherein, the second vibration system includes a second diaphragm fixedly supported on the magnetic circuit system and a second voice coil that drives the second diaphragm to vibrate and produce sound; the magnetic circuit system includes a first magnetic gap and a second magnetic gap, the first magnetic gap is arranged around the second magnetic gap; the first voice coil is inserted in the first magnetic gap and drives the first diaphragm to vibrate to generate low-pitch sound, the second voice coil is inserted in the second magnetic gap and drives the second diaphragm to vibrate to generate high-pitch sound.

3. The sounding device as described in claim 2, wherein, the auxiliary magnet group is separated from the primary magnet group to form the first magnetic gap, and the magnetic yoke is annular; the primary magnet and the inner wall of the magnetic yoke together form an inner cavity; the main pole plate includes a main pole plate body fixed to the primary magnet, and a protruding part of the main pole plate extending from the inner periphery of the main pole plate body into the inner cavity; the auxiliary magnet cover is fixed on the side of the main pole plate body away from the magnetic yoke; the primary magnet and the magnetic yoke which jointly surround the protruding part of the main pole plate, and together with the protruding part of the main pole plate form the second magnetic gap with an opening facing the second vibration system; the protruding part of the main pole plate is a hollow ring.

4. The sounding device as described in claim 3, further comprising an annular support rack fixed on a side of the

12

magnetic yoke away from the frame, wherein a peripheral support of the second diaphragm is fixed on the side of the support rack away from the magnetic yoke; the magnetic circuit system and the second vibration system together form a lower cavity, and the lower cavity is connected with the second magnetic gap.

5. The sounding device as described in claim 4, wherein, the second diaphragm includes a vibration part of the second diaphragm spaced from the magnetic yoke, a suspension of the second diaphragm extending from the outer periphery of the vibration part of the second diaphragm, and a connection part of the second diaphragm which is bent and extended from the suspension of the second diaphragm to the support rack; the connection part of the second diaphragm is fixed to the support rack; the second vibration system also includes a second skeleton; the side of the second skeleton close to the magnetic circuit system is fixed to the second voice coil, the side of the second skeleton away from the magnetic circuit system is fixed to the vibration part of the second diaphragm.

6. The sounding device as described in claim 5, wherein, the second skeleton includes an annular a first fixed part, and an elastic arm that is bent and extended from the inner side of the first fixed part, and a second fixed part extending from the elastic arm away from the first fixed part; the connection part of the second diaphragm and the support rack are respectively fixed on opposite sides of the first fixed part, the vibration part of the second diaphragm and the second voice coil are respectively fixed on opposite sides of the second fixed part; the auxiliary magnet group includes the auxiliary magnet fixed on the magnetic yoke, and the auxiliary pole plate covered and fixed on the side of the auxiliary magnet away from the magnetic yoke; the second skeleton also includes a third fixed part that is bent and extended from the outside of the first fixed part to the direction of the frame; the auxiliary pole plate is fixed to the frame, the third fixed part is fixed to the side of the auxiliary pole plate away from the frame; the frame is rectangular; the number of the auxiliary pole plate is two, the two auxiliary pole plates are respectively located on opposite sides of the long axis of the frame.

7. The sounding device as described in claim 3, wherein, the first vibration system further includes a first skeleton which is annular, the first voice coil is fixed on one side of the first skeleton close to the magnetic circuit system; the first diaphragm includes a first folded ring which is annular and a second folded ring which is annular; the first folded ring is arranged around the second folded ring and is spaced apart from the first folded ring; the second folded ring is arranged to surround the auxiliary magnet, the inner peripheral side of the second folded ring is fixed to the outer side of the auxiliary magnet; the first skeleton acts as the dome of the first diaphragm, the outer peripheral side is fixed to the inner peripheral side of the first folded ring, the inner peripheral side is fixed to the outer peripheral side of the second folded ring; and the outer peripheral side of the first folded ring is fixed on the frame.

8. The sounding device as described in claim 7, wherein, the first skeleton includes a first section which is annular, and a second section bent and extended from the inner peripheral side of the first section to the first voice coil, and a third section that is bent and extended from the inner peripheral side of the first section to the direction of the magnetic yoke; the first voice coil is fixed on the side of the second section close to the magnetic yoke, the side of the second section away from the magnetic yoke is fixed to the outer peripheral side of the second folded ring; the first vibration system further includes an elastic support assem-

13

bly arranged spaced from the first folded ring; one end of the elastic support assembly is fixed on the frame, and the other end of the elastic support assembly is fixed on the third section.
